UNITED STATES PATENT OFFICE.

HAROLD CALLAHAN, OF INDEPENDENCE, KANSAS.

PUMP RIG OR JACK.

Application filed May 10, 1924. Serial No. 712,283.

To all whom it may concern:

Be it known that I, HAROLD CALLAHAN, a citizen of the United States, residing at Independence, in the county of Montgomery and State of Kansas, have invented certain new and useful Improvements in Pump Rigs or Jacks, of which the following is a specification.

My invention relates to improvements in pumping apparatus, and has particular reference to improvements in pump jacks.

The operation of deep wells, is increasing rapidly, owing to the production getting into deeper territory. It is customary, in pumping deep wells, to use the equipment of a standard rig or jack, that has been employed to drill the well. The use of this standard rig or jack has not proven wholly satisfactory, since the stroke of the same is too short to obtain the best results. It has become recognized that in the pumping of deep oil wells, a short and fast stroke, will not pump as much fluid in a given time, as a longer and slower stroke. Further, a longer and slower stroke will reduce the whip, with a consequent reduction in breakage to the sucker rods and other parts.

An important object of the invention is to provide means of the above mentioned character, which are adapted to apply upon a standard rig or jack, without rebuilding the same, or without increasing the power to drive the equipment.

A further object of the invention is to provide means for increasing the length of the stroke and decreasing the speed of the same.

A further object of the invention is to provide means to counter-weight or balance the weight of the load of the sucker rods and movable parts of the equipment.

A further object of the invention is to provide guide means for the suspension element supporting the sucker rods, to prevent oscillation of the connecting parts.

A further object of the invention is to provide means of the above mentioned character which is simple, strong and inexpensive.

A further object of the invention is to provide means of the above mentioned character, in the nature of an attachment to be applied to the standard pump rig or jack.

Other objects and advantages of the in-

vention will be apparent during the course of the following description.

In the accompanying drawings forming a part of this specification, and in which like numerals are employed to designate like parts throughout the same,

Figure 1 is a side elevation of apparatus embodying my invention,

Figure 2 is a transverse section taken on line 2—2 of Figure 1,

Figure 3 is a front end elevation of the suspension means and guide means therefor,

Figure 4 is a transverse section taken on line 4—4 of Figure 1,

Figure 5 is a detail longitudinal section 70 through one of the segmental guides, and,

Figure 6 is a detail transverse section through the same.

In the drawings, wherein for the purpose of illustration is shown a preferred embodiment of my invention, the numeral 10 designates a post or standard, suitably mounted upon a base 11. This post or standard is provided with diagonal braces 12. Arranged above the post 10 is a walking beam 13, suitably pivotally connected, near its center, with the top of the post 10, as indicated at 14. Arranged to one side of the post 10 are vertical standards 15, carrying at their upper ends a transverse shaft 16, upon which is rigidly mounted a band wheel 17. The shaft 16 carries a crank 18.

The band wheel is driven by a belt 19, engaging a pulley 20, which may be driven directly from an engine or motor. If desired, the pulley 20 may be driven by a counter pulley 21, engaged by a belt 22, engaging the rotating pulley of a prime mover, such as a motor or engine. The construction of the parts above enumerated, are those of the ordinary or standard rig or pump jack, which may be used in drilling an oil well, and also employed in pumping the same, by producing a short stroke.

My invention resides in the provision of means, in the nature of an attachment, which is adapted to be applied to or associated with these parts, whereby the stroke of the jack may be increased, without the application of additional power to drive the same.

In accordance with my invention, I provide an extension beam 23, arranged upon the inner end of the walking beam 13, and clamped thereto by U-bolts 24 or the like. This extension beam projects outwardly be-

yond the end of the walking beam for a substantial distance, as shown. Arranged beneath the walking beam and its extension, is a supplemental walking beam 24', pivotally mounted at its inner end, as shown at 25, with the upper end of a post or standard 26. The extension beam 23 and supplemental walking beam 24 are disposed upon the same side of the post 10, and these elements are arranged in the same vertical plane. Of course the pivot 25 of the supplemental walking beam is spaced from the pivot 14, as shown.

The corresponding outer ends of the walking beam extension 23 and the supplemental walking beam 24 are pivotally connected by means of a link 27, held beneath plates 28, connected to these parts by bolts 29, as shown.

20 The numeral 30 designates a pitman, the upper end of which is equipped with a yoke 31, pivoted within a block 32, secured to the supplemental walking beam 24, near its center, by means of U-bolts 33. The lower 25 end of the pitman is provided with a suitable opening or bearing for the pivotal reception of a pin 34, adapted to be inserted in any one of selected openings 35, formed in the crank 18. The openings 35 are longitudinally spaced upon the crank 18, in order that the length of the stroke of the pitman 30, may be varied, as desired.

25 The numeral 36 designates a counter-weight, formed of concrete or any other suitable material, and slidable upon vertical guides 37. This counter-weight is connected with a flexible suspension element 38, such as a steel cable, extending upwardly, and secured to the free end of the walking beam 30 extension 23. The counter-weight is employed to counter balance the weight of the sucker rods, and associated elements.

35 Arranged upon the forward end of the walking beam 13 is a block 39, having a groove formed upon its upper face for receiving a cylindrical rod or cross head 40, having transverse openings for the reception of bolts 41, which pass through the parts 39 and 13, as clearly shown in Figure 50 3. This cylindrical cross head, Figure 5, is provided with tapered transverse openings 42, for the reception of the upper ends of flexible suspension elements 43, such as steel cables or the like. These ends are held 55 within the openings by means of babbittting. The flexible cables extend downwardly and are secured in a similar manner within transverse openings, formed in a lower cross head 44. This lower cross head has a central transverse cylindrical opening 45, rotatably receiving the polish rod 46, having a block 47 clamped thereon. This polish rod is connected with the sucker rods within the tube 47', as is well known.

The flexible elements or cables 43 travel

within grooves 48, Figure 6, formed in the outer face of segmental guides 49. These segmental guides have their upper ends bent into eyes 50, which receive the ends of the cross head 40, and preferably encircle the 70 openings 42. The lower ends of the segmental guides 49 are provided with eyes 51, receiving a transverse pin 52, provided in its ends with transverse openings to receive cotter pins 53 or the like. A diagonal U- 75 shaped brace 54 is provided, having eyes at its ends to receive the pin 52, and the transverse portion of this brace is held within a bracket 55, which may be longitudinally adjustably mounted upon the lower surface of the walking beam 13, by any suitable means.

In the operation of the apparatus, it will be seen that the rotation of the crank 18 reciprocates the pitman 30, which in turn oscillates the supplemental walking beam 23. This supplemental walking beam will transmit this oscillation to the main walking beam 13, but the main walking beam will be moved through a longer stroke and at a slower speed, as is obvious.

In view of the foregoing description, it will be seen that I can take the ordinary rig or pump jack, and apply my improvements thereto, whereby the stroke of the walking beam may be prolonged and rendered slower, without the increase of power to the rig. I also contemplate building the complete apparatus, embodying my invention, in which event the main walking beam would have one end thereof longer than the other, and hence the invention is not necessarily restricted to the idea of the same being embodied in an attachment. 100

It is to be understood that the form of my invention herewith shown and described is to be taken as a preferred embodiment of the same, and that various changes in the shape, size, and arrangement of parts, may be resorted to, without departing from the spirit of my invention, or the scope of the subjoined claims. 105

Having thus described my invention, I claim:

1. A standard pump or jack, comprising an upstanding post, a walking beam pivoted near its center upon the post, pumping means connected with one end of the walking beam, a bearing arranged upon one side of the post and in general vertical alignment with the opposite end of the walking beam, a transverse shaft held within the bearing, a crank carried by the shaft, and means to drive the shaft; in combination with an extension beam secured to the end of the walking beam above said shaft and serving to increase the length of one arm of the walking beam, a standard disposed between said shaft and said post, a supplemental walking beam having its inner 110
2. A standard pump or jack, comprising an upstanding post, a walking beam pivoted near its center upon the post, pumping means connected with one end of the walking beam, a bearing arranged upon one side of the post and in general vertical alignment with the opposite end of the walking beam, a transverse shaft held within the bearing, a crank carried by the shaft, and means to drive the shaft; in combination with an extension beam secured to the end of the walking beam above said shaft and serving to increase the length of one arm of the walking beam, a standard disposed between said shaft and said post, a supplemental walking beam having its inner 115
3. A standard pump or jack, comprising an upstanding post, a walking beam pivoted near its center upon the post, pumping means connected with one end of the walking beam, a bearing arranged upon one side of the post and in general vertical alignment with the opposite end of the walking beam, a transverse shaft held within the bearing, a crank carried by the shaft, and means to drive the shaft; in combination with an extension beam secured to the end of the walking beam above said shaft and serving to increase the length of one arm of the walking beam, a standard disposed between said shaft and said post, a supplemental walking beam having its inner 120
4. A standard pump or jack, comprising an upstanding post, a walking beam pivoted near its center upon the post, pumping means connected with one end of the walking beam, a bearing arranged upon one side of the post and in general vertical alignment with the opposite end of the walking beam, a transverse shaft held within the bearing, a crank carried by the shaft, and means to drive the shaft; in combination with an extension beam secured to the end of the walking beam above said shaft and serving to increase the length of one arm of the walking beam, a standard disposed between said shaft and said post, a supplemental walking beam having its inner 125
5. A standard pump or jack, comprising an upstanding post, a walking beam pivoted near its center upon the post, pumping means connected with one end of the walking beam, a bearing arranged upon one side of the post and in general vertical alignment with the opposite end of the walking beam, a transverse shaft held within the bearing, a crank carried by the shaft, and means to drive the shaft; in combination with an extension beam secured to the end of the walking beam above said shaft and serving to increase the length of one arm of the walking beam, a standard disposed between said shaft and said post, a supplemental walking beam having its inner 130

- end pivotally connected with said standard and projecting outwardly toward the outer end of the extension beam, a link pivotally connecting the outer end of the supplemental end of the walking beam and the outer end of the extension beam, and a pitman connected with the supplemental walking beam between its ends and connected with the crank.
- 10 2. A standard pump or jack comprising a post, a walking beam pivoted near its center to the post, pump means connected with one end of the walking beam, bearing means arranged upon one side of the post and in general vertical alinement with the opposite end of the walking beam, a shaft held within the bearing means, a crank carried by the shaft, and means to drive the shaft; in combination with an extension beam secured to the free end of the walking beam and projecting outwardly beyond the same to increase the length of one arm of the walking beam, a support arranged between the bearing means and post, a supplemental walking beam having its end pivotally connected with the support and its outer end projecting outwardly toward the free end of the extension beam, and terminating inwardly of the same, a link pivotally connected with the outer end of the supplemental walking beam and with the outer end portion of the extension beam, a pitman pivotally connected with the supplemental walking beam adjacent to its center and pivotally connected with said crank, a substantially vertical guide arranged beneath and in general vertical alinement with the free end of the extension beam, a weight slideable upon the guide, and a cable connecting the weight and the free end of the extension beam and arranged outwardly of the free end of the supplemental walking beam.
- 15 20

In testimony whereof I affix my signature.

HAROLD CALLAHAN.
